RING TRAVELER

Stuart H. Sherman, La Grange, and Robert J. Clarkson, Hogansville, Ga., assignors to United States Rubber Company, New York, N. Y., a corporation of New Jersey

Application March 27, 1942, Serial No. 436,442

8 Claims. (Cl. 57—125)

This invention relates to rings and travelers for spinning and twisting machines and more particularly to an improved ring traveler for use upon a twister frame for twisting filaments together to form a ply strand or cord. The invention has been developed primarily for use in twisting fine wire filaments together to form a ply strand or cord.

In twisting wire filaments it has been customary heretofore to twist the filaments on a stranding machine in accordance with conventional practice of forming strands or cords in the cable industry. The use of textile equipment for the purpose of twisting wire filaments has not been considered feasible because of the different characteristics of the metal filament as compared with textile yarns or threads. We have found that strands can be satisfactorily twisted from wire filaments with textile equipment by providing a specially constructed ring traveler. Essentially the invention resides in a ring traveler having means associated therewith for providing a relatively large curvature on that portion of the traveler which is engaged by the wire filaments, and which is also constructed to direct the filament to one side of the axis of the spinning spindle.

Among the objects of our invention are to provide means whereby wire filaments may be twisted on conventional textile twisting equipment; to provide a ring traveler for conventional textile equipment which produces the minimum distortion on the twisted strands; to provide a ring traveler which may be easily associated with conventional textile equipment and which will thereby permit the stranding of wire filaments; and, to provide a ring traveler for wire strands which may be easily and economically constructed. These and other objects and advantages will appear more fully in the following detailed description when considered in connection with the accompanying drawing in which:

Fig. 1 is a perspective view, partly in section, and diagrammatically illustrating a portion of a textile twisting machine incorporating features of our invention;

Fig. 2 is a perspective view of a ring traveler illustrating in detail the principal embodiment of the invention;

Fig. 3 is a front elevational view thereof; and, Fig. 4 is a perspective view of a modified form of a ring traveler.

With reference to the drawing and in particular to Fig. 1, our invention is illustrated diagrammatically to include portions of a conven-

tional textile twisting machine. As a source of supply, a plurality of spools 11, 12 and 13 are suitably supported by the frame of a conventional textile twisting machine. Each of these spools retains a supply of wire filaments 14. For purpose of illustrating the invention, three supply spools are shown from which three wire filaments are withdrawn to provide ultimately a wire strand formed of the three filaments. It is to be understood, however, that two or more filaments may be twisted together to form a ply strand and that such ply strands may be subsequently twisted together to form a cord.

Below the supply spools 11, 12 and 13 is positioned a guide strip 15 having an aperture 16 extending therethrough. The three filaments 14 are guided through the aperture 16 to form in effect a plurality of filaments associated in substantially parallel relationship. Good results have been obtained by twisting steel wire filaments having a gauge of .0059 inch. A positive feed mechanism is provided for the purpose of moving the wire at a fixed and uniform rate. This means comprises a pair of shafts 17 and 18 to which are secured multiple grooved pulleys 19 and 20, respectively. One of the shafts 17 or 18 is driven at a constant rate of speed by conventional means not shown. Each pulley 19 and 20 is provided with five grooves so as to permit the parallel associated filaments 14 to form four complete belts or reaches around the pulleys 19 and 20. These plurality of wrappings around the pulleys 19 and 20 provide adequate surface contact with sufficient tension to insure a uniform drive movement of the wire filaments. Leaving the last groove in the pulley 20, the wire filaments extend upwardly and pass around a sheave 21 rotatably mounted on a pin 22 extending from an arm 23 attached to a rod 24. The rod 24 is, in turn, supported by some part of the frame of the conventional textile twisting machine.

Positioned directly below the sheave 21 is a spindle 25 supported by a bearing in a base plate 26 and capable of being driven by means of a pulley 27 secured to the spindle. The spindle 25, its supporting means and drive are constructed entirely in accordance with conventional textile machinery construction. A spool 28 is shown positioned on the spindle 25. A conventional ring rail 29 is positioned above the base plate 26 and is adaptable for vertical movement. A ring 30 is attached in fixed relationship with the ring rail 29 concentrically with the spindle 25.

Associated with the ring 30 is a traveler 31. This traveler is shown in particular in Figs. 2 and 3. Essentially the traveler comprises a clip-like member having return bent portions 32 and 33 at opposite ends of the clip member. As thus far described, the traveler is of conventional construction. Attached to the face of the traveler is a tubular member 34 of arcuate shape and secured diagonally to the face of the traveler by means of a soldering or brazing operation. The diagonal position of the tube 34 is shown particularly in Fig. 3. The angle 35 with which the tube is positioned relative to the traveler is such that the strand 36 formed from the twisted filaments 14 will be directed to a point representing the mean distance between the empty and the full capacity of the spool 28. It is preferable that the tube 34 should have as large a radius as possible consistent with the associated equipment. We have found that good results can be obtained by maintaining a radius to the center of the tube of approximately $\frac{1}{8}$ inch. It is desirable, however, that this radius should not be less than $\frac{1}{16}$ inch.

Fig. 4 illustrates a modified form of a ring traveler. In this modification the path of curvature for the strand 36 is embodied in the structure of the traveler itself. Essentially the traveler comprises a clip-like member 37 having return bent portions 38 and 39 at opposite ends of the clip member. At one side at the top of the clip member is an upturned portion 40 which forms a channel having a smooth radius extending along the top of the clip member as viewed from its front face. Near the bottom of the clip member 37 and at the side opposite the upturned portion 40 is an arcuate out-turned portion 41. The combined effect of the clip member 37 with the out-turned portion 41 and upturned portion 40 is such that a smooth diagonal channel is formed extending across the clip member 37 for receiving the strand 36 and for changing its direction of travel in an arcuate path.

As thus shown and described, it is believed apparent that we have provided a novel and efficient traveler which in combination with conventional textile equipment makes it possible to twist wire, glass, and other non-textile filaments without setting up undue stresses in the filaments. The traveler however may also be used to advantage upon textile filaments, and while we have shown a preferred embodiment of the invention, it is to be understood that it is susceptible of those modifications, which appear obviously within the spirit of the invention and as defined in the scope of the appended claims.

Having thus described our invention, what we claim and desire to protect by Letters Patent is:

1. In combination with a spinner or twister ring and spindle, a ring traveler adapted to slide upon said ring and provided with a filament receiving channel that extends lengthwise of the traveler throughout a substantial portion of the length of this traveler in a slightly diagonal direction.
10. In combination with a spinner or twister ring, a ring traveler for said ring, and an arcuate filament guiding tube attached to the traveler and extending a substantial distance lengthwise of the traveler in a slightly diagonal direction.
15. In combination with a spinner or twister ring, a ring traveler for said ring, and an arcuate guiding tube attached to the traveler to extend a substantial distance lengthwise of the traveler and diagonally thereof, said tube having a filament guiding radius of at least $\frac{1}{8}$ inch.
20. In combination with a spinner or twister ring, a ring traveler for said ring, and filament guiding means associated with the traveler and constructed to extend a substantial distance lengthwise of the traveler in a slightly diagonal direction.
25. In combination with a spinner or twister ring, a ring traveler for said ring, and filament guiding means associated with the traveler and constructed to extend lengthwise of the traveler for the major portion of the latter's length and slightly diagonal thereof.
30. In combination with a spinner or twister ring, a ring traveler for said ring, and filament guiding means associated with the traveler and constructed to guide the filament in an arc extending slightly diagonally of the length of the traveler and which arc has a radius of at least $\frac{1}{8}$ inch.
35. In combination with a spinner or twister ring, a ring traveler for said ring and filament guiding means associated with the traveler and constructed to guide the filament in an arc extending slightly diagonally of the length of the traveler and which arc has a radius of at least $\frac{1}{8}$ inch.
40. In combination with a spinner or twister ring, a ring traveler for said ring and provided with a filament guiding portion extending slightly diagonally of the length of the traveler and formed with an arcuate guiding surface for the filament and which surface has a radius of at least $\frac{1}{8}$ inch.
45. In combination with a spinner or twister ring, a ring traveler comprising a clip having return bent portions at its upper and lower ends, one side of the upper portion of the clip being provided with an arcuate up-turned portion, the opposite side of the lower face of this clip having an arcuate out-turned portion, whereby a filament guiding arcuate path is formed to extend slightly diagonally of the length of the clip.
50. STUART H. SHERMAN.
